UNITED STATES PATENT OFFICE.

WILLIAM H. GRAY, OF GREEN POINT, BROOKLYN, NEW YORK, ASSIGNOR TO
THE GLEN COVE MACHINE COMPANY, (LIMITED,) OF SAME PLACE.

WOOD-SURFACING MACHINE.

SPECIFICATION forming part of Letters Patent No. 355,012, dated December 28, 1886.

Application filed May 15, 1886. Serial No. 202,239. (No model.)

To all whom it may concern:

Be it known that I, WILLIAM H. GRAY, of Green Point, Brooklyn, in the county of Kings and State of New York, have invented a new and useful Improvement in Wood Surfacing or Planing Machines, of which the following is a specification.

My invention, although all or some of its features may be embodied in wood-planing machines generally, is particularly intended for surfacing-machines in which an upper cutter-head and upper system of feed-rolls are supported by a main frame, and a lower cutter-head and lower system of feed-rolls are supported by a vertically-movable lower frame. In such machines the lower cutter-head is frequently near the rear end of the machine; from which the lumber issues, and has arranged above it a platen to hold the lumber against the cutter-head, and there is a feed-roll beyond or rearward of the platen. The removal of this upper platen and feed-roll from their operative positions greatly facilitates access to the lower cutter-head for the purpose of securing and adjusting the cutters or knives thereon; and one feature of my invention consists in a novel construction and combination of parts whereby the upper platen and adjacent feed-roller, either or both of them, may be moved upward and downward and held in operative position. The lower movable frame which carries the lower cutter-head and system of feed-rollers is frequently raised and lowered by means of screws and nuts at four points near the corners of the said movable frame, said screws and nuts serving to connect the movable frame with the fixed frame of the machine.

Another feature of my invention consists in a novel combination of the screws and nuts with the main frame and lower movable frame, whereby the screws are prevented from binding in the nuts and are enabled to adjust themselves into true alignment with the screws to insure the easy adjustment of the lower movable frame.

The several combinations which are included in my invention are hereinafter described, and pointed out in the claims.

In the accompanying drawings, Figure 1 is a side elevation of a wood surfacing or planing

machine embodying my invention. Fig. 2 is a longitudinal vertical section thereof. Fig. 3 is an end elevation, partly in transverse section, looking at the rear end of the machine, or 55 toward that end from which the lumber issues; and Fig. 4 is a plan of the machine.

Similar letters of reference designate corresponding parts in all the figures.

A designates the main frame of the machine, 60 which may be constructed in several parts suitably connected together, and B designates a movable lower frame, which may be adjusted upward and downward within the main frame by means hereinafter described, and over which 65 the lumber is fed through the machine.

In the upper portion of the main frame is an upper cutter-head, C, and in the vertically-movable frame B is a lower cutter-head, C'. Arranged opposite these cutter-heads are platens or a bed, D, and a platen, D', as best shown in Fig. 2, the bed D being supported by the movable lower frame, B, opposite the upper cutter-head, C, and the platen D' being supported opposite the lower cutter-head, C'. 75

In order to properly feed forward the lumber through the machine, I have represented upper feed-rolls E E' E'', which are supported at the upper portion of the main frame, and I have also represented lower feed-rolls F F', as 80 supported by the movable lower frame, B. These rolls may, most or all of them, be geared together, so as to positively drive them by gearing which is well known in machines of this class, and of which no particular description 85 is here necessary. I would here remark, however, that upon the upper feed-roll E' is a gear-wheel, e, upon the upper feed-roll E'' is a gear-wheel, e', which gears into and receives motion through an intermediate pinion, e'', 90 (shown in Fig. 4, and by dotted lines in Figs. 1 and 2,) and upon the lower feed-roll F' is a gear-wheel, e''. I have particularly described these several gear-wheels in order that my mechanism for transmitting motion from the 95 upper system of feed-rolls to the lower system carried by the movable frame B, and which I hereinafter describe, may be clearly understood.

In order to afford facility of access to the lower cutter-head, C', for the purpose of adjusting knives or cutters thereon, or for any

other purpose, it is advantageous to have the upper platen, D', and the upper feed-roll E² removable from their operative position, which is shown in Fig. 2 in full lines. To accomplish this result I do not mount the platen D' and the roller E² directly in the main frame, but I support them in a movable upper frame, G, which is hinged at b, so that it may be swung upward in a plane transverse to the length of the platen D' and the roll E², as is shown by dotted lines in Fig. 2. The boxes of the feed-roll E² are supported in the frame G, and are capable of vertical adjustment therein by means of screws b'. The platen D' may also be raised and lowered in the frame G by means of screws c, at opposite ends thereof, and which are geared together by a cross-shaft, c', and bevel-gearing c², so that when said cross-shaft is turned the screws c will be turned simultaneously and the platen D' raised or lowered in the frame G. To provide for swinging the frame G upward and downward, as described, and also to hold it in fixed position when it is swung down to the position shown in Fig. 1, I employ screws H, which are fitted to swivel-nuts h, and which serve to connect the hinged upper frame, G, with the main frame A. In this example of my invention the screws H are fitted to bearings h', which are swiveled or pivotally connected with the main frame A. Consequently when these screws are turned, the hinged upper frame, G, will be swung upward, as shown by dotted lines in Fig. 2, and the screws will assume an oblique position, as also shown in Fig. 2. The pivoted or swiveled nuts and bearings h h' provide for the oblique position of the screws H, without the binding of the screws in said nuts or bearings. A single screw at one side of the hinged frame G might suffice for the purpose; but I prefer to employ screws H at opposite sides of said frame, as best shown in Fig. 3, and such screws may be connected and operated simultaneously by a cross-shaft, h², and bevel-gears h³.

From the above description it will be seen that the screws H not only serve to raise the hinged frame G and lower it, but they also serve to hold the hinged frame, with its platen D' and roll E², down in operative position on the main frame A.

To raise and lower the lower frame, B, I have represented upright screws I, which are four in number, and journaled in bearings d in the main frame A, as shown best in Figs. 2 and 3. The screws I are arranged in pairs, one pair being at or near one end of the movable lower frame, B, and the other pair of screws being at or near the other end of said movable lower frame. These screws are connected by cross and longitudinal shafts d' and bevel-wheels d², so that all may be operated simultaneously, and by means of a shaft, d³, which extends to the front of the machine, and is there provided with a crank-handle, d⁴, the screws may all be turned in unison. These screws I engage nuts I', on which the movable

lower frame, B, is supported. As here shown, this lower frame consists of parallel side bars or portions, b², extending lengthwise of the machine, and cross bars or portions b³, connecting said side portions, b², near opposite ends. The cross-bars b³ have in them sockets or circular bearers b⁴, which receive the nuts I', and these nuts have projecting studs or trunnions b⁵, which are fitted to recesses or concave notches b⁶ in the cross portions b³ of the lower frame. This gives the nuts I' a swiveled or pivoted connection with the lower frame, B, and enables the nuts to adapt themselves properly to their screws and avoids any binding or canting of the screws and nuts.

I will now describe how power is transmitted from the upper system of feed-rolls E, &c., to the lower system of feed-rolls F, &c., without interference from the vertical adjustment of the lower frame, B, carrying said feed-rolls. J designates the main shaft of the machine, and J' is a counter-shaft which receives motion from the main shaft J by a pair of cone pulleys or drums, i, (best shown in Figs. 1 and 4,) and which are connected by a belt, i'. From a pulley on the shaft J' motion is transmitted by a belt, i², to a pulley, i³, which is comprised in the upper system of feed-gearing, and through wheels and pinions, which it is not necessary to particularly describe, and which may be combined, as is usual in machines of this character, motion is transmitted from the pulley i³ to the upper feed-roll, E'. From the gear-wheel e of this upper feed-roll E' motion is transmitted through a train of wheels to the gear-wheel e² on the lower feed-roll F'. This train of wheel or expansion gears is here represented as composed of two wheels, e⁴ e⁵, which gear with each other and respectively with the wheels e³ e. The wheels e⁴ e⁵ are journaled upon studs carried by a bar, e⁶, which is fulcrumed or pivoted concentric with the wheel e³, and the upper end of this bar is connected by a link, e⁷, to hold the wheel e⁵ in engagement with the wheel e. To additionally support the wheels e⁴ e⁵, I have represented their centers as connected by a link or bar, e⁸, arranged on the side of the wheels opposite the long bar e⁶. By this arrangement and combination of expansion-gears motion is transmitted from the wheel e on the upper feed-roll to the wheel e³ on the lower feed-roll without interference from the vertical movement or adjustment of the frame B and the lower feed-rolls supported by it.

The upper cutter-head, C, is, as here represented, driven by belts C² from pulleys J² on the shaft J, and one of these belts passes over and bears with frictional contact on a second belt, C³, driving around a pulley, J³, and from thence to a pulley on a journal of the lower cutter-head, C'. The belt C³ is driven by frictional engagement of the belt C² with it, as has been before done in planing-machines, and it will be seen that as the movable frame B, carrying the lower cutter-head, C', is raised or lowered the tension of the belt C³ will be

varied unless some means be employed to preserve a substantially uniform tension in said belt. The means for this purpose, which is best represented in Fig. 1, consists of two pulleys, $l\bar{l}$, under and over which one member or portion of the belt C^3 passes, and which are journaled in a swinging frame, $\bar{l}^2$. From the frame $\bar{l}^2$ an arm, $\bar{l}^4$, extends upward, and has connected with it an operating and locking bar, $\bar{l}^4$, toothed or notched at its under side to engage a tooth or detent, $\bar{l}^5$. When it is desired to swing the frame $\bar{l}^2$ so as to adjust the rollers $l\bar{l}$ to produce more or less deflection of the belt C^3 as it passes between them, the rod or bar $\bar{l}^4$ may be lifted off from the tooth $\bar{l}^5$ and shoved back or drawn forward to swing the frame $\bar{l}^2$. When the rod or bar $\bar{l}^4$ is released, it is supported by the tooth or detent $\bar{l}^5$, and its notches come into automatic engagement with said tooth or detent.

What I claim as my invention, and desire to secure by Letters Patent, is—

1. In a wood-planing machine, the combination, with the main frame and an upper platen, of a frame carrying the upper platen and hinged to swing upward in a plane transverse to the length of the platen and a screw or screws and swiveled nut or nuts connecting the main frame and hinged frame, and by which the hinged frame may be moved and held in operative position, substantially as herein described.

2. The combination, with the main frame and an upper feed or bearing roll, of a frame carrying the said roll and hinged to swing upward in a plane transverse to the length of the roll, and a screw or screws and swiveled nut or nuts connecting the hinged frame and main frame, and by which the hinged frame may be moved and held in position, substantially as herein described.

3. The combination, with a main frame and

an upper frame carrying an upper platen and feed-roll, either or both, and hinged to swing upward in a plane transverse to the length of the platen or roll, of swiveled bearings on the hinged frame and swiveled nuts on the main frame, screws journaled in the swiveled bearings and fitting the nuts, and gearing connecting the screws for turning them simultaneously, substantially as herein described.

4. The combination, with a main frame supporting an upper cutter-head and system of feed-rolls, of a movable lower frame supporting a cutter-head and system of feed-rolls, upright screws I , journaled in the main frame and arranged in pairs at opposite ends of the movable lower frame, cross and longitudinal shafts d^1 , and bevel-gears d^2 , connecting the screws and nuts I' , having trunnions b^5 , which are transverse to the axes of the screws, and which are received in recesses or open bearings on the under side of the movable frame, substantially as herein described.

5. The combination, with a main frame supporting an upper cutter-head and system of feed-rolls, of a movable lower frame supporting a cutter-head and system of feed-rolls, upright screws I , journaled in the main frame and arranged in pairs at opposite ends of the movable lower frame, cross and longitudinal shafts d^1 , and bevel-gears d^2 , connecting the screws, a shaft, d^3 , extending to the front of the machine and geared with the screws and their connecting-shafts, and nuts I' , having the trunnions b^5 , which are transverse to the axes of the screws, and which are received in recesses or open bearings on the under side of the movable lower frame, substantially as herein described.
